UNITED STATES PATENT OFFICE.

FRANK M. ALLEN, OF CLAYMONT, DELAWARE, ASSIGNOR TO GENERAL CHEMICAL COMPANY, OF NEW YORK, N. Y., A CORPORATION OF NEW YORK.

FURNACE

Application filed November 29, 1921. Serial No. 518,501.

To all whom it may concern:

Be it known that I, FRANK M. ALLEN, a citizen of the United States, and resident of Claymont, Brandywine Hundred, county of New Castle, and State of Delaware, have invented certain new and useful Improvements in Furnaces, of which the following is a specification.

My invention relates to furnaces and 10 more particularly to rotary furnaces designed primarily for chemical and metallurgical purposes and fired by means of liquid fuel. The object of my invention is to provide such furnaces with a combustion 15 chamber of novel construction capable of being rotatably adjusted to successively present different portions thereof at the place of greatest wear and which, in all of its positions, includes a self-supporting top 20 arch; a further object of the invention is to construct the combustion chamber in such a manner that its ends may be reversed with respect to the burner and thereby increase the life of said chamber. My invention 25 contemplates further an arrangement in which there are no dead spaces around the flame for the collection of dead air or other gases and in which the combustion chamber, or more specifically, the lining thereof, 30 is constructed in sections capable of being readily removed and replaced for purposes of repair and the like. Other objects of the invention will appear from the description hereinafter and the features of novelty will 35 be pointed out in the appended claims.

In the accompanying drawings, which 40 illustrate a specific embodiment of the invention without defining its limits, Figure 1 is a diagrammatic sectional elevation of the furnace and its combustion chamber; Fig. 2 is an end view of the combustion chamber; Fig. 3 is an enlarged detail section of a preferred form of oil burner which 45 may constitute the firing means, and Fig. 4 is an end view thereof.

In the drawings, 10 represents a rotary furnace of any conventional type which 50 may be supported in any well known way and includes all features customarily found in such furnaces as, for instance, the usual manhole nozzles through which the product is periodically discharged in batches. The furnace, as shown, is provided with an 55 exit opening 11 at one end adapted for connection with the customary stack (not

shown) in the usual manner; at its other end, the furnace 10 is provided with an inlet opening 12, as shown in Fig. 1. The combustion chamber *a* comprises a metal cylinder 13 lined with fire brick or other 60 refractory material 13^a, said lining being preferably constructed in sections capable of being readily removed from the cylinder 13 whenever this is desired or found necessary. The cylinder 13 is mounted upon a 65 cradle so as to be rotatable about its axis, said cradle consisting of rollers 14 rotatably supported upon a carriage 15 which itself is carried by wheels 16, so as to be capable of being moved toward and away from the 70 furnace 10, preferably upon a suitable track 16^a. The construction further includes a wall 17 located upon the carriage 15 adjacent to the one end of the combustion chamber *a* and having an aperture 18 into 75 which the end of the oil burner 19 projects. As shown in Fig. 1, the combustion chamber *a* preferably is located so as to be spaced both from the inlet opening 12 of the furnace 10 and from the wall 17, to form an 80 annular air inlet spaces *b* and *c* respectively, the purpose of which spacing will appear more fully hereinafter. The burner 19 may be connected by means of a pipe 20 with a source of oil or other liquid fuel and with 85 a source of atomizing agent, such as compressed air, through the medium of a pipe 21; suitable valves 22 and 23 may be located in the pipes 20 and 21 for controlling the flow of the fuel and of the air respectively. The burner may conveniently be mounted by means of a swing-joint 24, so as to be capable of being swung aside to 90 permit the removal of the combustion chamber *a* for the purpose to be more fully 95 described hereinafter. While any conventional form of burner and particularly of liquid fuel or oil burner may be used for firing the furnace, a multiple jet burner of the type illustrated, by way of example, in 100 Figs. 3 and 4, is preferred for this purpose. This burner comprises an atomizing nozzle 25 having its exit end provided with a wall 26 in which a plurality of apertures 105 27 are formed, said nozzle 25 being in communication with the air pipe 21; a fuel pipe 28 connected with the oil line 20 extends into the nozzle 25 and terminates in a plurality of jets 29, each of which has its exit 110 end in registry with one of the apertures 110

27 and in close proximity to the wall 26 of the nozzle 25. This type of burner gives a shorter and more efficient flame than a single jet burner of equal capacity, and 5 while the same is preferred, it is not to be understood as precluding the use of single jet burners in place thereof.

In practice, the flame *d* from the burner 19 passes first through the aperture 18 in the 10 wall 17, then through the cylindrical combustion chamber *a* and then into the furnace 10. At the same time, air enters the combustion chamber *a* through the space *c* and a further amount of air passes into the furnace 15 10 through the space *b*. It has been found that with the use of this construction the refractory material 13^a of the combustion chamber *a*, as well as the refractory material located in those parts of the furnace which adjoin the space *b* lasts a comparatively long time. This fact may be explained as follows:

The flame *d* is surrounded both within the combustion chamber and within the inlet opening 12 of the furnace by a layer of comparatively cool air which insulates the refractory material from the flame, has a direct cooling action on such material and reduces the temperature within the combustion chamber *a* by reducing the amount of heat reflected from such material. The air introduced through the space *b* is burned in the furnace proper in a zone just beyond the inlet opening 12, that is, the final mixing 30 and combustion occurs at a place where the flame flares or expands into the furnace so that such air cannot be designated as "false air," that is to say, air which merely interferes with proper combustion. In other 35 words, air is admitted at *c* to protect the walls of the combustion chamber *a* while air is admitted at *b* to protect the walls along the inlet passage to the furnace and at the same time to finish combustion of the oil as 40 soon as possible after the latter has entered the furnace proper. Thus the maximum heat value is extracted from the gas by the furnace, combustion is high, giving an average of fourteen per cent CO₂, and the walls 45 of the combustion chamber and furnace inlet are prevented from reaching dangerously destructive, high temperatures. The amount of air which passes through the space *b* depends, in part, upon the dimensions of such 50 space, and is further regulated by regulating the draft in the stack with which the exit opening 11 of the furnace 10 is connected, preferably in such a manner that the amount of air passing through the space *b* is sufficient 55 to cause the flame, in passing such space, to fall slightly inward and away from the refractory lining and to permit the air to flow between the flame and such lining. The air entering through the space *c* exerts 60 a similar protecting action on the refractory

material 13^a adjoining such space within the combustion chamber *a*.

As the top of the combustion chamber *a*, which gets the most wear, finally becomes worn, the combustion chamber *a* may be rotated upon the rollers 14 about its axis so that the worn portion of the lining is shifted to a position in which it is exposed, to a lesser degree, to the action of the flame of the burner 19. At the same time this adjustment of the aforesaid cylinder brings a different portion of the combustion chamber *a* to a position in which it serves as the top of such chamber in place of that portion of the refractory material which has become worn. 70 The combustion chamber *a* may also be reversed end for end so as to bring that end which is farther from the burner and accordingly is subjected to the greatest wear, into a position adjoining the wall 17, its place being taken by the other end which has received by far less wear. In this way the life of the combustion chamber may be said to be at least four times the life of a chamber which cannot be rotated and reversed in 80 the manner described. The adjustment of the composite cylinder, both as to rotation and reversibility, may be facilitated by first swinging the burner 19 aside and then moving the carriage 15 in a direction away from 85 the furnace 10.

With the arrangement described, the combustion chamber produces a self-supporting arch for the top thereof; that is to say, the combustion chamber, being cylindrical, 100 forms its own top arch regardless of the position to which the cylinder may be adjusted. Furthermore, there are no dead spaces around the flame or pockets or corners in which dead air or other gases may collect. 105 In addition to the above, the combustion chamber, the lining of which is built in sections, may easily be repaired if one of said sections becomes worn by taking out such damaged section and replacing it with another. 110

In some cases, for instance when a less concentrated flame is employed, the combustion chamber *a* may be so positioned as to engage with its opposite ends the wall 17 and the inlet end 12 of the furnace respectively. With this arrangement the protecting envelope of air is not present, but otherwise the advantages are the same as those previously set forth. 115

Various modifications in the specific form shown and described may be made within the scope of the claims without departing from the spirit of my invention.

I claim:

1. The combination of a furnace, a burner for firing the same and a rotatable combustion chamber located between said furnace and burner and having its opposite ends duplicates of each other whereby said combus- 120

tion chamber may be reversed with respect to said burner.

2. The combination of a furnace, a liquid fuel burner for firing the same, and a cylindrical combustion chamber located between said furnace and said burner and rotatable about its axis to different stationary positions whereby successive sections of said combustion chamber constitute the top thereof.

3. The combination of a furnace, a liquid fuel burner for firing the same, and a cylindrical rotatable combustion chamber located between said furnace and said burner and having its opposite ends duplicates of each other whereby said combustion chamber may be reversed with respect to said burner, said combustion chamber being adjustable about its axis to different stationary positions whereby successive sections of said combustion chamber may be made to constitute the top thereof.

4. The combination of a furnace having an entrance at one end, a wall spaced from said end and having an aperture, a burner in registry with said aperture and adapted to project a flame therethrough, and a combustion chamber located between said end of the furnace and said wall and having its one end spaced from said furnace end and its other end spaced from said wall to provide air inlets for surrounding the flame within the combustion chamber and within the entrance to the furnace with a layer of cool air.

5. The combination of a rotary furnace having an inlet end, a wall spaced from said inlet end and provided with an aperture, a burner located in registry with said aperture for projecting a flame therethrough and a cylindrical combustion chamber located between said end of the furnace and said wall and having duplicate ends spaced, respectively, from said furnace end and from said wall to provide air inlets whereby said flame within the combustion chamber and within the entrance to the furnace is surrounded by a layer of cool air, said combustion chamber being reversible with respect to said burner.

6. The combination of a rotary furnace having an inlet end, a wall spaced from said inlet end and provided with an aperture, a liquid fuel burner located in registry with said aperture for projecting a flame therethrough and a cylindrical combustion chamber located between said end of the furnace and said wall and having duplicate ends spaced, respectively, from said furnace end and from said wall to provide air inlets whereby said flame within the combustion

chamber and within the entrance to the furnace is surrounded by a layer of cool air, said combustion chamber being reversible with respect to said burner and being rotatably adjustable about its axis to cause successive portions thereof to constitute the top of said combustion chamber.

7. The combination of a furnace, a burner for firing the same and a combustion chamber located between said furnace and burner and having its opposite ends duplicates of each other whereby said combustion chamber may be reversed with respect to said burner, said combustion chamber comprising a metal cylinder and a plurality of sections of refractory material located within said cylinder to form a lining therefor.

8. The combination of a furnace having a firing inlet, a burner wall provided with an aperture, a burner projecting into said aperture, and a combustion chamber interposed between said inlet and said burner wall and having its ends spaced from the furnace inlet and from the burner wall respectively.

9. The combination of a furnace having a firing inlet, a combustion chamber located in operative relation to said inlet and mounted to turn about the longitudinal axis of said chamber, and means for producing combustion in said chamber.

10. The combination of a furnace having a firing inlet, a carriage movable toward and away from said inlet, and a combustion chamber arranged to be brought into and out of operative relation to said inlet by the movement of the carriage and mounted to turn about an axis parallel to the path of said carriage.

11. The combination of a furnace having a firing inlet, a carriage movable toward and away from said inlet, a burner wall mounted on said carriage, and a combustion chamber mounted on said carriage on the side of said wall which is toward the furnace, and adapted to be brought into operative relation to the furnace inlet, said chamber being mounted to turn about its longitudinal axis.

12. The combination of a furnace having a firing inlet, a carriage movable toward and away from said inlet, a rotatable combustion chamber mounted on said carriage and arranged to be brought into and out of operative relation to said inlet by the movement of the carriage, and a burner arranged to co-operate with said chamber and pivotally movable into and out of the path of movement of said chamber.

In testimony whereof I have hereunto set my hand.

FRANK M. ALLEN.
